UNITED STATES PATENT OFFICE.

GEORGE McWHIRTER, OF BETHLEHEM, PENNSYLVANIA.

AUTOMATIC TENSION DEVICE FOR LOOMS.

Application filed September 16, 1927. Serial No. 220,013.

This invention relates to tension devices for looms and has for its primary object to automatically maintain a uniform tension throughout the entire warp used in the manufacture of silk fabrics on weaving looms. It has been found that in the weaving industry that the slack in the warp results in producing rope and berry marks in the finished fabric and accordingly by employing 10 an automatic tension device, such as proposed by my invention, no slack is permitted to occur in the warp thereby eliminating the objectionable rope and berry marks in the finished fabric and thus enable the production of a superior grade of cloth.

The invention has for a further object the provision of an apparatus of this character of simple and practical construction, in which the parts employed in obtaining the 20 desired results are reduced to a minimum, which is inexpensive to manufacture and install in operative position upon a conventional type of loom and otherwise well adapted for the purposes for which the 25 same is intended.

Other objects and advantages reside in the special construction and combination of the various elements constituting the invention, reference being had to the drawings forming a part of this application, wherein:—

Figure 1 is a view in side elevation.

Figure 2 is a top plan view showing the tension device in operative position with respect to the shaft of the warp beam.

Figure 3 is a vertical sectional view taken substantially along a line 3—3 of Figure 2, and

Figure 4 is a similar view taken along a line 4—4 of Figure 2.

Referring to the drawings in detail, a warp beam of conventional construction is indicated at 5 having its ends supported by a driving yoke 6 mounted for rotation on a shaft 7. A U-shaped bearing support 8 is provided for the shaft having one side thereof bolted to the frame shown in dotted lines at 9.

A worm wheel 12 is arranged on the shaft 50 mounted upon the shaft, said ends being arranged outwardly with respect to the adjacent end of the bearing bracket 8, the bracket being arranged to extend normally at a horizontal position.

A worm wheel 12 is arranged on the shaft

for rotation therewith and positioned so as to extend between the open ends 11 of the bracket 10. A worm gear supporting bracket 13 is secured to the opposite ends of the bracket 10, having a shaft 14 extending vertically therethrough upon which the worm gear 15 is keyed for rotation therewith. The lower end of the shaft 14 extends through the bracket 13 and carries a bevel gear 16 thereon, said gear engaging a similar bevel gear 17 secured on one end of a shaft 18 rotatably supported in an arm 19 depending from the bracket 10.

The shaft 18 also carries a ratchet wheel 20 operatively engaged by a pawl 21 carried at one end of a reciprocating rod 22, which has its opposite end attached to a crank 23 secured on the crank shaft 24 of the loom. It will be noted from an inspection of Figure 1 of the drawings that the rod 22 is supported intermediate its ends upon the end of the shaft 7, which thereby limits the downward movement of the pawl 21 with respect to its engagement with the ratchet wheel 20.

A link 25 extends downwardly in an inclined position from the lower portion of the bearing support 8, to which one end of the link is fixedly bolted at 26, the opposite lower end of the link pivotally supporting 85 one end of a lever 27 adapted to support a weight 28 at the opposite end thereof. The weighted end of the lever 27 is provided with a series of notches 29 providing means for the adjustment of the weight thereon.

A rod 30 having a hook 31 formed at its lower end engages the lever 27 and supports the same in suspended position from a boss 32 formed on one of the arms of the bracket 10. The relative position of the lever 27 with respect to the bracket 10 is therefore constantly maintained by reason of the connection thereof by the rod 30.

In the operation of the device, as the thread is unwound from the warp beam 5, the shaft 7 is rotated and the bracket 10 is maintained in an upward position as shown in Figure 1 of the drawing by reason of the engagement of the worm wheel 12 with the worm gear 15. In such position the ratchet wheel 20 is in position for engagement by the pawl 21 which through its actuation by the crank shaft 24 will operate to intermittently rotate the ratchet wheel, which having a geared connection with the worm wheel 110

12 will facilitate the rotation of the warp shaft 7 whereby to aid in the unwinding of the thread from the warp. The tension of the thread during the unwinding operation is normally sufficient to maintain the bracket 10 in upward position against the force of the weight 28, but in the event the ratchet wheel 20 is operated too rapidly so as to cause a slack in the thread, the bracket 10 will swing downwardly whereby to cause the disengagement of the pawl 21 therefrom and the ratchet wheel will accordingly remain idle until the tension of the thread is again increased sufficiently to raise the bracket 10 upwardly. In this manner the proper tension is automatically maintained upon the thread during its entire unwinding operation without requiring the services of an attendant.

20 It is obvious that the invention is susceptible to various changes and modifications without departing from the spirit or scope of the appended claims and I accordingly claim all such forms of the device to which 25 I am entitled.

Having thus described my invention, what I claim as new is:—

1. In a warp tensioning device, a warp supporting shaft, a bracket pivotally mounted on said shaft, a worm gear carried by the bracket, a worm wheel mounted on the shaft operatively engaged therewith, a ratchet wheel carried by the bracket, means operatively connecting the same with said worm gear, a reciprocating rod, supporting means therefor limiting the downward movement of one end thereof, a pawl carried on said end engageable with the ratchet wheel, means operatively connecting the opposite end of the rod, a pivotally mounted lever, a weight attached at the free end thereof and a rod connecting said lever with the bracket whereby to move said ratchet out of engagement with said pawl upon a

decrease in the tension of the thread of said 45 warp.

2. In a warp tensioning device, a warp supporting shaft, a gravity actuated bracket pivotally supported on said shaft, a ratchet wheel mounted on the bracket, means operatively connecting the ratchet with the shaft and adapted to retain the bracket in a predetermined pivoted position by the tension of the warp and reciprocable operating means for the ratchet arranged for movement in a plane at right angles to the axis of the ratchet, said ratchet being movable relative to said plane of the operating means, and said operating means being free for movement upwardly during an upward 60 movement of the ratchet and limited in its downward movement whereby to regulate the extent of rotation of the ratchet in accordance with the increase or decrease in the tension of the warp. 65

3. In a warp tensioning device, a warp supporting shaft, a gravity actuated bracket pivotally supported on said shaft, a gravity actuated wheel mounted on the bracket, means operatively connecting the ratchet 70 with the shaft and adapted to maintain the bracket in a predetermined pivoted position by the tension of the warp, a reciprocably operable arm arranged for movement in a plane at right angles to the axis of the 75 ratchet, said arm being free for upward movement and limited in its downward movement, and a pawl carried by the arm engageable with the ratchet said ratchet being moveable relative to the pawl for engagement therewith at a predetermined position on the ratchet for regulating the ratio 80 of movement between the throw of the arm and the ratchet, in accordance with the increase or decrease in the tension of the warp. 85

In testimony whereof I affix my signature.

GEORGE McWHIRTER.
